CLAIM

The ornamental design for a circuit interrupter as shown and described.

DESCRIPTION

FIG. 1 is a right perspective view of the circuit interrupter; FIG. 2 is an enlarged view of detail 2 in FIG. 1; FIG. 3 is a left perspective view of the circuit interrupter; FIG. 4 is an enlarged view of detail 4 in FIG. 3; FIG. 5 is an upper perspective view of the circuit interrupter; FIG. 6 is an enlarged view of detail 6 in FIG. 5; FIG. 7 is a front elevational view of the circuit interrupter; FIG. 8 is an enlarged view of detail 8 in FIG. 7; FIG. 9 is a left side elevational view of the circuit interrupter; FIG. 10 is a right side elevational view of the circuit interrupter; FIG. 11 is a rear elevational view of the circuit interrupter; FIG. 12 is a top plan view of the circuit interrupter; and, FIG. 13 is a bottom plan view of the circuit interrupter. The long-dash lines are for illustration of the boundary between claimed subject matter and unclaimed subject matter only and form no part of the claimed design. The short-dashed lines are for illustration of environmental subject matter only and form no part of the claimed design. The dot-dashed lines are for indication of those portions of FIGS. 1, 3, 5, and 7 that are enlarged in FIGS. 2, 4, 6, and 8, respectively, only and form no part of the claimed design.
